CARBON DIOXIDE LIQUEFIER

Harry S. Houghton, San Marino, Calif.

Application October 29, 1934, Serial No. 750,544

4 Claims. (Cl. 220—3)

This invention pertains to an apparatus for liquefying solid carbon dioxide, and pertains particularly to an apparatus adapted to receive solid carbon dioxide, cause an at least partial liquefaction thereof and permit withdrawal of gaseous carbon dioxide.

One of the particular objects of the invention is to provide a device having an inclosed chamber adapted to withstand a relatively high internal pressure and provided with a quickly and easily removable closure means whereby the chamber may be easily opened, charged with solid carbon dioxide, and sealed.

The device of the present invention may comprise, essentially, a vertically disposed elongated cylindrical chamber closed at its lower end and provided with a removable closure means at its upper end, said removable closure means being of such nature as to provide an opening of substantially the full cross-sectional area of said cylinder when removed from said cylinder. Suitable valve and conduit means may be provided associating said chamber with a reserve chamber and providing for dispensing gaseous carbon dioxide.

The attached drawings show a preferred embodiment of the invention and referring thereto:

Fig. 1 is a partly broken-away side elevation of the device showing the liquefying chamber, gaseous carbon dioxide reserve chamber, and the associated valve mechanisms;

Fig. 2 is a transverse section thereof taken on line 2—2 in Fig. 1;

Fig. 3 is a side elevation detail thereof taken on line 3—3 in Fig. 1;

Fig. 4 is a partly broken-away sectional elevation of the liquefying chamber portion of the device, showing a removable carrier device disposed within said chamber portion.

Referring to the drawings, the complete apparatus may comprise a pressure vessel 1 having a closed lower end wall 2 provided with a drain cock 3 and a removable closure means 4 at the upper end of the device. The vessel 1 may be provided with a suitable supporting standard such as a spun metal base 5 for the purpose of maintaining the apparatus in an upright position. Adjacent the upper end of the vessel 1 I provide a vapor outlet line 6 provided with a cut-off valve 7, communicating with a header 8 which is preferably provided with a pressure gauge 9 and connecting through cut-off valve 11 to a pressure storage receptacle 12, which is preferably of smaller size than the pressure vessel 1. To provide for withdrawal of gaseous carbon dioxide from the apparatus, I provide a branch conduit

13 leading from the header 8 and provided with a pressure regulating valve 14, gauge 15, and threaded outlet connection 16 adapted to receive a connection 17 for dispensing of the gas. The receptacle 12 is preferably secured to the vessel 1 in some suitable manner, as by means of one or more hook members 18 secured to the vessel 1 and a corresponding number of eye members 19 secured to the receptacle 12, whereby said receptacle may be removably supported on said vessel.

The removable closure means of the present invention may comprise an inner compression member such as a disc 21 of circular shape disposed within a circular recess 22, constituting a charging opening having cylindrical side walls, in the upper end of the vessel 1 and provided with an annular shoulder or recess 23 within which may be disposed a packing member 24. Immediately above the recess 23 I provide an outer compression member such as an annular ring 25 fitting snugly within the recess 22 in engagement with said packing member 24 and of such size as to also fit within the recess 23, so that when the said ring is brought into compressive engagement with the packing member 24, it will extend within said recess to prevent said packing from being squeezed out. In order to restrain the compression ring 25 against upward movement, I provide a plurality of removable head sections 26 and 27 positioned outwardly of said compression ring, which head sections, when assembled in their preferred relation, encompass a circular area of greater radius than the recess 22, and I provide a radially extending recess 28 in the vessel 1 defining shoulder means 28a adjacent the upper end of the recess 22 within which the peripheral portions 29 and 31 of the sections 26 and 27 may be disposed in locking position. The head sections 26 are preferably of comparable shape and provided with two parallel opposing sides 26a, extending inwardly from the circular peripheral portions 29 to an inner edge 26b which is preferably parallel to a tangent to such peripheral edge at a point thereon intermediate the two parallel edges 26a. The head sections 27 may be of segmental shape and of such radial depth d that when this dimension is added to one-half the length of the side 26b of the section 26, the total will be just slightly less than the radial dimension of the vessel 1 at the recess 28 and the length l of such segments is less than the diameter of the recess 22 so that when the sections 26 are lifted out and one of the sections moved inwardly as shown in dot-dash lines at 27a, said section

may be lifted free of the recess 28. The sections 26 and 27, when assembled as shown in Fig. 2, will thus define a rectangular and preferably square space 32, centrally of the vessel 1, and in order to maintain the sections in their outward position with their peripheral edges disposed within the recess 28, I provide a plate 33 having a depending boss 34 of a shape corresponding to the opening 32, which may be inserted within the outer end of the recess 22 into position maintaining the sections 26 and 27 in such outward position. To provide for bringing the various portions of the closure means 4 into pressure-resisting relation, I provide a bolt 35 secured to the plate 21 and extending through a suitable aperture in the plate 33 into position for threaded engagement with a suitable clamping nut or the like 36.

I may also provide a removable carrier device 20 which may be inserted within the vessel 1 for the purpose of holding the solid carbon dioxide with which the apparatus is charged, and for keeping the solid carbon dioxide and the formed liquid carbon dioxide out of contact with the side and bottom walls of said vessel and thus positively preventing any undue chilling of the material of which said walls are formed. This removable carrier may comprise a cylindrical member 41 provided with a closed lower end 42, and a side wall 43 having a rim portion 44 adapted to rest against the lower edge or shoulder 46 provided by the recess 23. The side wall 43 of the carrier 41 is preferably provided with a plurality of openings 45 adjacent the upper end of the device, through which gaseous carbon-dioxide may pass. The outside diameter of the carrier 41 is preferably such with respect to the inside diameter of the vessel 1 that an appreciable separation of said carrier and said vessel is obtained, as at a. 40 The capacity of the carrier 41 is materially less than the volumetric capacity of the vessel 1, so that when said vessel is charged with solid carbon dioxide by filling said carrier, the amount of gaseous carbon dioxide formed will not be such as to cause an excessively high pressure to be developed in case the vessel and its contents should reach the critical temperature of carbon dioxide. It will be appreciated that the apparatus may be employed without the carrier 41 being used, provided that the operator is careful to fill the vessel with no more than the desired quantity of solid carbon dioxide, according to the above set forth requirements. The spacing *a* between the carrier 41 and the vessel 1 is of 50 considerable advantage in insulating the main body of solid or liquid carbon dioxide within said carrier in the event that the vessel is subjected to an external heating for any reason, in that there would be no sudden evaporation of gaseous carbon dioxide from the material within the carrier. This spacing also permits the evolved gaseous carbon dioxide to pass from the carrier 41 downwardly around the same into the space below said carrier.

65 In employing the device for the dispensing of gaseous carbon dioxide, the closure means 4 is removed and the member 41 either removed and a charged carrier of comparable shape inserted in place thereof, or filled with solid carbon dioxide 70 by dumping the same into said carrier, or the vessel itself filled to the desired extent, as above described. After the desired quantity of solid carbon dioxide is placed within the vessel, the compression plate 21 is dropped into the recess 75 22 and allowed to rest against the upper edge of

the rim 44, or against the shoulder 46 if the carrier 41 is not employed, it being understood that ordinarily the packing member 24 will be carried with the plate 21 and will not have to be handled separately. The compression ring 25 is then dropped into place in engagement with the packing member, and the two segmental sections 27 are placed in position within the recess 28, after which the two sections 26 are dropped into place and forced outwardly into their correct position within said recess. When thus assembled, as shown in Figs. 1 and 2, the head sections 26 and 27 are disposed above the outer compression member 25, in position to restrain the latter against upward movement, while the engagement of the outer edge portions of said head sections with the shoulder 28a serves to prevent upward movement of said head sections, thereby locking the entire sealing assembly including members 21, 24, and 25, against outward movement by 10 pressure within the vessel. The plate 33 is then placed in position above and extending over the head sections 26 and 27, with the boss 34 fitting within the opening 32, and the nut 36 is screwed down over the bolt 35. As the plate 21 is brought 15 upwardly due to tightening of the nut 36, the packing 24 will be firmly clamped between the ring 25 and the bottom of the recess 23 in said plate 21, being substantially confined within said recess, and will also be crowded outwardly against 20 the side wall of the recess 22, while the head sections 26 and 27 will be held against displacement from the positions shown in Fig. 2, due not only to their being tightly clamped between cover plate 23 and the outer compression member 25, but 25 also to the disposition of the boss 34 within the central opening 32. It will be appreciated that in this particular type of closure means a relatively soft packing material may be employed, in view of the fact that any pressure developed 30 within the vessel 1 due to evaporation of the solid carbon dioxide will exert an increased pressure against the plate 21, and due to the immobility of the ring 25, a further compression 35 of the packing member 24 will be realized and a 40 very effective sealing of the upper end of the device will be obtained. As the evaporation of the solid carbon dioxide within the vessel 1 progresses, the pressure will increase within said vessel and the gaseous carbon dioxide may be 45 withdrawn through the conduit 6 by opening the valve 7, and the valve 11 may be left open until the maximum pressure is realized within said vessel, after which the valve 11 may be closed 50 and the volume of gaseous carbon dioxide within 55 the receptacle 12 be retained as a reserve supply for use during the recharging of the vessel 1, and gaseous carbon dioxide under the desired pressure may be continually withdrawn at 16 under suitable control by the pressure regulating valve 14. 60 It will be appreciated that the valves 7 and 11, as well as the valve 14, may be provided with safety plugs 51, if desired, according to common 65 practice in the art.

It will be appreciated that the particular shapes 65 of the head sections shown at 26 and 27 are not absolutely essential to this invention, in view of the fact that alternatively shaped sections of comparable utility may be employed. The present 70 described shape and arrangement of parts, however, provides a simple, easily fabricated, and easily assembled arrangement, and for this reason this particular design has been chosen for illustration.

I claim:

1. In a carbon dioxide liquefier, a pressure vessel provided with a charging opening at its upper end and a recess around said opening providing a downwardly facing shoulder; inner and outer compression members removably disposed within said charging opening below said shoulder; a packing member between said compression members in position for sealing engagement with the interior of said opening; a plurality of removable head sections positioned above said outer compression member in position to prevent upward movement thereof and having their outer edge portions engaging said shoulder; a plate disposed above and extending over said head sections; and means engaging said plate and said inner compression member and operable to draw the same toward one another, to securely clamp said head sections between said plate and outer compression member and compress said packing member between said inner and outer compression members.
2. In a carbon dioxide liquefier, a pressure vessel provided with a charging opening at its upper end, and with a wall surrounding said opening and recessed outwardly from said opening to provide downwardly facing shoulder means; inner and outer compression members removably disposed within said opening; a packing member between said compression members in position for sealing engagement with said wall; a plurality of removable head sections positioned above and in engagement with said outer compression member and having their outer portions engaging said shoulder means; a plate disposed above and extending over said head sections and serving to hold said head sections in position; and means associated with said plate and said inner compression member for drawing said plate and member toward one another.
3. In a carbon dioxide liquefier, a pressure vessel provided with a charging opening and a recess around said opening providing a shoulder extending outwardly from said opening; inner and outer compression members removably disposed within said charging opening; a packing member between said compression members in position for sealing engagement with the interior of said opening; a plurality of removable head sections positioned outwardly of said outer compression member in position to restrain said outer compression member against outward movement and having peripheral edge portions disposed within said recess in position to engage said shoulder, said head sections providing, when assembled, a central opening; a plate disposed outwardly of and extending over said removable head sections and provided with means projecting inwardly from said plate and extending within said central opening and engaging said head sections to hold the same outwardly in engagement with said shoulder, and means engaging said plate and said inner compression member to draw the same toward one another, thus clamping said head sections between said plate and said outer compression member and compressing said packing member between said inner and outer compression members.
4. In a carbon dioxide liquefier, a pressure vessel provided with a charging opening at its upper end and with a wall surrounding said opening and recessed outwardly therefrom to provide downwardly facing shoulder means; a compression plate disposed within said opening; a packing member disposed above said plate adjacent the periphery thereof in position for sealing engagement with said wall; an annular compression member disposed above and in engagement with said packing member; a plurality of removable head sections disposed above said annular compression member and in position to limit upward movement of said annular compression member, said head sections having outer edge portions extending within the outward recess in said wall and engaging said shoulder means; a cover plate disposed above and in engagement with said head sections; and means associated with said cover plate and said compression plate for drawing said plates toward one another to clamp said head sections in said position and to compress said packing member.

HARRY S. HOUGHTON.
